UNITED STATES PATENT OFFICE.

WILLIAM J. MAGINNIS, OF PHILADELPHIA, PENNSYLVANIA, ASSIGNOR TO ROYAL ELECTROTYPE COMPANY, OF PHILADELPHIA, PENNSYLVANIA, A CORPORATION OF PENNSYLVANIA.

PROCESS OF INCORPORATING ENGRAVED PLATES WITH ELECTROS IN A SOLID PLATE.

Application filed November 7, 1924. Serial No. 748,433.

My invention relates to a process of incorporating original engraved plates, photo-engraved plates, zinc etchings, electrotypes and other separate printing plates in the 5 same composite printing-plate and to composite plates as thus constructed.

The main purpose of my invention is to supply a solid back to individual plates each forming less than the entire printing 10 face, which are mounted in a common composite printing plate.

A further purpose is to shave or form the partial plate or plates to the thickness of an engraved plate or plates intended to form 15 part of the same composite printing plate and then to mount the partial plate or plates and engraved plates upon a backing of uniform thickness to form the composite printing plate.

20 A further purpose is to avoid the defects arising from the soldering together of parts of printed plates containing such printing plates, as generally practiced at the present time.

25 Further purposes will appear in the specification and in the claims.

I have preferred to illustrate my invention by but one form, selecting for the illustration a form which has proved to be practical, 30 efficient, thoroughly reliable and inexpensive and which at the same time well illustrates the principles involved.

Figure 1 is a top plan view showing a completed printing plate illustrating my invention.

35 Figures 2 to 5 are sections to enlarged scale corresponding in position to line 7-7 of Figure 1, showing the backing and two of the plates separated from it and progressively illustrating, with the description various steps in my process.

40 Figure 6 is a section corresponding to line 7-7 of Figure 1 showing the parts assembled for seating.

45 Figure 7 is a section upon line 7-7.

In the drawings similar numerals indicate like parts.

45 In the printing art it has been customary for years to use electrotype plates for all long runs in order to save expensive original engraved or photo-engraved plates from

the wear which would speedily destroy them and for the further purpose of making it possible to use a number of duplicate plates at the same time. However, in some 55 cases where the run is to be short the customer desires that the original engraved plate or a photo-engraved plate be used instead.

The engraved plate, photo-engraved plate, 60 generally referred to herein for convenience as a "printing" plate seldom if ever comprises the entire printing surface. Even where it presents the entire subject matter which the customer desires to display it requires the addition of the caption and folio and in a great many cases it is used in connection with or is interspersed in other matter to be printed, so that frequently one or more printing plates of one character must 65 be incorporated with one or more printing plates of another character to form the complete printing plate. Sometimes half a dozen or more printing plates are so incorporated in one composite plate. 75

It has been customary to match up the edges of the several printing plates and solder them together. Some printing plates, of which the electrotype is the most common example, are much thicker than others, of 80 which the original engraved plates form a very good example. My invention will therefore be illustrated by application to these two examples, it being understood that any thicker plate can be incorporated with any 85 thinner plate or plates in the same manner, cutting all the thicker plates to the thickness of the thinnest plate.

The more usual thickness of the electrotype to be used on metal bases for letter 90 press work is one hundred and fifty-two thousandths of an inch (.152") and the thickness of the engraved plate has been much less, more usually either sixty-three thousandths of an inch (.063"), or forty-eight thousandths of an inch (.048"). The thicknesses .152" and .063", respectively will be used in carrying the example through in this specification. 95

In the previous practice the engraved plate 100 or plates has or have been backed to the electrotype thickness of one hundred and fifty-

two thousandths of an inch (.152") and the backed engraved plate or plates and the electrotype plate or plates have been soldered together to make up the complete printing plate.

Because these composite edge-secured plates have been much thinner than the type high (.918) provided between the press and the printing surface, these composite plates have been temporarily attached in use to or upon so-called patent blocks or bases of which a number are well known in the art so that the combined thickness of the patent base or block and the composite plate upon it has been approximately .918; thus treating the composite plate exactly as an electrotype plate of .152 thickness would be treated.

It is difficult to make the soldered joint equal in strength to the body of the plate. Even where a plate is weakened in one or more places by routing, the routed portions of the plate often stand up better than the soldered joints. The difficulty has been very much increased by the presence of tin in the solder which tin is attacked by the printing ink with consequent honeycombing and weakening of the solder.

With the best of care in placing and supporting the composite plate in the press a slight flexure of the plate takes place during printing. As a result of this the sharp lines of division where the parts have been soldered yield first to give the flexure and, where the runs of the press are long, the plates frequently break. Sometimes they break even in short runs. This requires that the plates be made over again and if the plates break in the press it often does serious damage to the press and endangers those working on it.

My invention is designed to overcome this difficulty by treating all of the plates alike, cutting down the electrotypes, here taken as typical of the thicker plates, to the thickness of the engraved plates, here taken as typical of the thinner plates, and giving them a common and therefore a solid backing which can be and shall be kept free from lines of division. When intended for incorporation with engraved plates, electrotypes can, of course, be made initially of standard engraved plate thickness.

In the drawing a single complete printing plate only is illustrated and I have selected the one in which the engraved part 10 of the complete plate is diagonal and is flanged by diagonally placed electrotyped matter. Consequently the stiffening and strength contributed by the engraved plate is along irregular lines, exaggerating the bending tendency at its edges. Of the parts 11, 12, 13 and 14 here treated as electrotyped, and which could of course be of other or different characters, 13 is irregular in general outline and

12 and 13 are located within the lower left and upper right sections of the plate on opposite sides of the diagonal engraved part.

In the best means of assemblage known to me the backing 15 comprises a solid sheet of electrotype material upon which the engraved and electrotype portions of the plate are to be placed and to which they are to be attached. Its thickness is approximately eighty-nine thousandths of an inch (.089").

I shave the electrotypes from their normal thickness of one hundred fifty-two thousandths of an inch (.152") to a thickness of sixty-three thousandths of an inch (.063") to agree with the thickness accepted as that of the engraved plate. If their intended use be known at the start, the electrotypes will be shaved initially to the common thickness. Obviously plates of other thicknesses can be accommodated and the intention is to shave the thicker plates to the thickness of the thinnest plate to be incorporated so that all of the plates used are of the same thickness and that less than the initial thickness of the thicker plates. The backing will, or course, be selected to make up the difference.

The plate 10 is accordingly shown as of the same thickness in all of the views but the plate 13, (as well as each other electrotype used) initially having the thickness indicated in Figure 2, is shaved at the back to the dotted line, making the other electrotypes (as seen in 13 in the other figures) the same thickness as the engraved plate 10.

In Figure 3 the plates are ready for assembly and, for convenience are shown, as in Figures 2, 4 and 5, in position directly above the plate at which they are to be secured upon the backing 15.

The backing is then coated with a flux represented at 16 in Figure 4. I have found rosin and alcohol satisfactory but know that there are various other well known fluxes which may be used. Among the many fluxes rosin and alcohol flux is one of a number which have the advantage of not requiring immediate use.

On top of the flux I place one or more sheets of tin foil 17 applied in Figure 5 and the plates are distributed on top of the tin foil as seen in Figure 6. They are then sweated to the backing by the application of heat and slight pressure, the heat being preferably but not necessarily applied from the under side of the backing. The flux and sheet of tin are greatly exaggerated in thickness in Figures 4, 5 and 6.

The other electrotypes are shaved and applied as in the case of 13 and the application being preferably concurrently therewith.

It is desirable to fasten the plates against lateral movement before the sweating operation so as to avoid shifting of the plates and this fastening can be done by punching them with a sharp instrument so as to punch out

a portion at the back into the backing, by pinning them to the backing or by other convenient means. Pins 18 are shown in Figures 6 and 7 and the finished plate is seen in Figure 7, in which the exaggerated thicknesses of the flux and tin have been dropped and the plates and backing lie together.

My invention not only makes a stronger composite plate, increasing its life and making its use safer both as regards human life and damage to the press, but effects a very considerable saving in time in manufacture and can be carried out to a larger extent by machinery. Manufacture is made to depend less upon the skill of the operator, and to require less care by the operator. It can therefore be carried out reliably by workmen less skilled in the art.

My invention thus provides a composite plate complete with backing for attachment to or mounting upon a patent block or base and adapted for removal and replacement in its entirety from and to the block or base without readjustment or setting of the distances between the respective elements from which the printing surface is made up.

I recognize that in view of my disclosure others will be able to make changes in my process and plate, by which all or a part of the benefit of my invention may be secured without copying the form of the invention disclosed by me. It is therefore my purpose to include herein all such modifications and changes as come within the reasonable spirit and scope of my invention.

Having thus described my invention, what I claim as new and desire to secure by Letters Patent is:—

1. The method of incorporating two printing plates having different standard thickness in the same composite printing plate adapted for attachment to a patent block or base, which consists in forming the normally thicker plate to a thickness corresponding to the thickness of the thinner plate and permanently mounting both plates upon a common backing having a thickness correspond-

ing to the difference between the thickness of the thinner plate and the thickness desired for the composite printing plate.

2. The method of incorporating an engraved plate and an electrotype plate having approximately the thickness of the normal electrotype plate in a common composite printing plate which consists in shaving the electrotype plate to a reduced thickness as compared with that of the ultimate printing plate and soldering both plates upon a common backing whose thickness approximates that shaved from the electrotype plate.

3. The method of incorporating an engraved plate and an electrotype plate in the same printing plate of approximately electrotype thickness, which consists in giving the same thickness to the plates by shaving, placing them upon a common backing and sweating them into union with the backing.

4. A composite printing plate of thickness suitable for attachment to a patent block or base comprising a backing of uniform thickness, and a printing plate and an electrotype plate, each having the same thickness as the other and united to the backing.

5. A composite printing plate of thickness suitable for attachment to a patent block or base comprising a backing free from soldered edge joints and an electrotype plate and an engraved plate rigidly united to the backing and having their printing surfaces at the same height from the backing.

6. A printing plate of thickness suitable for attachment to a patent block or base having a solid backing and printing surfaces permanently mounted thereon respectively electrotyped and engraved.

7. A printing plate of thickness suitable for attachment to a patent block or base comprising two printing plates having different recognized initial standard thicknesses and a solid backing underlying both and to which both are permanently united to give the same printing height.

WILLIAM J. MAGINNIS.
